(57) **CLAIM**

The ornamental design for a port sealer, as shown and described.

DESCRIPTION

FIG. 1 is a side perspective view of a port sealer showing my new design;

FIG. 2 is a left side elevation view thereof;

FIG. 3 is a right side elevation view thereof;

FIG. 4 is a top side elevation view thereof;

FIG. 5 is a bottom side elevation view thereof;

FIG. 6 is a top elevation view thereof; and,

FIG. 7 is a bottom elevation view thereof.
